METHOD OF PRODUCING HOLLOW SET-SCREWS.

1,243,818.

Specification of Letters Patent.

Patented Oct. 23, 1917.

Application filed December 14, 1914, Serial No. 877,177. Renewed March 20, 1917. Serial No. 156,226.

To all whom it may concern:

Be it known that I, NORMAN W. CUMMINS, a citizen of the United States, residing at Bridgeport, in the county of Fairfield and State of Connecticut, have invented certain new and useful Improvements in Methods of Producing Hollow Set-Screws, of which the following is a specification.

My present invention pertains to an improved method of producing hollow set-screws, the procedure for carrying out the same and the advantages of which will be hereinafter set forth in detail, reference being had to the annexed drawings, wherein:

15 Figure 1 is a sectional view of the die in which the stock from which the screw is formed is placed, the stock and the knock-out punch or die being shown in full;

20 Fig. 2 a similar view, the partially-formed screw-blank being shown in section and the initial forming punch in full;

Fig. 3 a like view with the final forming punch in position;

25 Fig. 4 a sectional view of a screw formed from a blank subjected to the action of but a single punch; and

Fig. 5 a similar view of a screw formed as the result of the successive action of a series of punches.

30 In the drawings, 1 denotes the die, having a recess 2 therein, cylindrical in cross-section, open at the top and having a downwardly-inclined or tapering bottom 3. An opening 4 extends through the lower portion 35 of the die, terminating in the center of the bottom 3. A knockout die 5 extends through said opening 4 and projects into the die-cavity, the upper end of said die 5 being rounded, as at 6. As will be seen upon reference to the drawings, the knock-out die is so positioned that the margin of the rounded portion, or the line where such portion and the cylindrical portion of the die come together or join, will preferably coincide with the edge of the opening 4 in the bottom 3; this for a purpose which will presently appear.

40 The blank to be transformed into a screw (indicated by 7, Fig. 1) is cylindrical in shape, and will preferably be cut from a rod or wire of circular cross-section and of a diameter substantially equal to that of the die-recess 2. It is dropped into said recess and the lower end thereof comes to rest upon

the upper rounded end 6 of the knock-out die.

A punch 8, having its lower end 9 polygonal in cross-section (preferably hexagonal) and its extreme lower end slightly convex, is forced centrally into the upper end 60 of the blank, whereby the metal is caused to flow both downwardly and upwardly, filling the space in the lower portion of the die and likewise passing upwardly about the polygonal portion of the punch. Such operation will form a screw (minus the threads, which, of course, are formed after the removal of the screw-blank from the die) such as is shown in Fig. 4. This screw may be all-sufficient for certain purposes, but 70 preferably I carry the process further, whereby a deeper recess or sink is formed in the screw-blank, while at the same time the metal is more thoroughly condensed and the upper edge is likewise given a better 75 finish. To this end I employ a second punch, 10, the lower end 11 of which is of the same outline as the end 9, but is of slightly smaller diameter, say, one-sixty-fourth of an inch, while at the same time 80 said punch, above the polygonal portion, is provided with a shoulder 12, the punch-body above said shoulder substantially filling the die-recess 2. Said second punch 10 is forced downwardly in the previously-formed opening in the stock, sinking into the stock, and causing a further flow of the metal, both upwardly and around the polygonal section 11, the shoulder 12 finally coming into contact with the upper edge of the metal, whereby 85 the central depression in the stock is deepened and the metal further condensed by being forced into contact with the side faces of the section 11 and also against the shoulder 12.

90 The action of the punch swages the metal into close and intimate contact with the walls of the die, over the rounded end of the knock-out die 5, and also about itself, whereby the upper edge of the screw-blank 100 is finished by the shoulder, and the interior faces 13 of the countersink are rendered smooth. Upon the completion of the sinking of the punch 10, the knock-out or kick-out die 5 is actuated in an upward direction, thereby removing the screw-blank from the recess 2 of die 1. It will be found that 105 the lower end of the blank will present a

sharp and clean edge 14 at the junction of its beveled face 15 and the central cupped depression 16, formed by the rounded end 6 of the kick-out die 5, so that it will set or 5 adapt itself closely to any surface against which it may be forced.

It is, of course, conceivable that instead of forming the lower end of the screw with a cupped or depressed portion, the knock-out die may be omitted and the bottom of 10 the die-recess continued down to a sharp point, in which case the screw-blank would present a pointed lower end.

The final step in the process of forming 15 the screw is to thread the same exteriorly.

A set-screw made in accordance with the above method is homogeneous throughout, owing to the fact that it is formed from a solid piece of metal and swaged into shape. 20 The threads, when cut, are sharp and smooth without the slightest trace of a pit or chatter, indicating an exceedingly dense structure.

Having thus described my invention, what 25 I claim is:

1. The process of making hollow set-screws, which consists in placing a solid piece of stock of substantially cylindrical form in a die having the same cross-section 30 and likewise having a tapering bottom; sinking a punch into the stock, thereby causing the metal to flow upwardly about said punch and also downwardly to conform to the bottom of the die; and finally threading the 35 blank thus produced.

2. The process of making hollow set-screws, which consists in placing a solid, substantially cylindrical piece of stock in a die having a cross-section of like contour, 40 and likewise having a downwardly-tapering bottom; sinking a punch, polygonal in cross-section, downwardly into the central upper portion of the stock, thereby causing the laterally confined stock to flow upwardly about the punch and also downwardly to conform 45 to the bottom of the die; and finally threading the blank thus produced.

3. The process of making hollow set-screws, which consists in placing a solid cylindrical piece of stock in a die having a cross-section of like contour; thereafter sinking a punch, polygonal in cross-section, into the upper central portion of the stock; then sinking a second punch of like but 55 somewhat smaller dimensions into the opening produced by the first punch, said second punch likewise having a shouldered portion above the polygonal section, whereby the upper marginal portion of the stock, as 60 well as the body thereof, will be condensed as the punch reaches its limit of inward movement; and finally threading the blank thus produced.

4. The process of making hollow set-screws, which consists in placing a solid cy-

lindrical piece of stock in a die having a cross-section of like contour and a tapering bottom; thereafter, while the stock is confined in the die, causing the same to flow downwardly to fill the bottom of the die 70 and likewise upwardly about a punch sunk downwardly into the upper face of the stock; and finally threading the blank thus produced.

5. The process of making hollow set-screws, which consists in placing a solid cylindrical piece of stock in a die having a cross-section of like contour; then subjecting the stock to the action of a punch having a polygonal cross-section; then to a punch 75 of like but smaller cross-section, said punch having an outwardly-projecting shoulder above its punching portion, adapted to contact with the upper edge of the wall of the blank to confine and condense the same; and 80 finally threading the blank thus formed.

6. The process of making hollow set-screws, which consists in placing a solid cylindrical piece of metal stock in a die having a cross-section of like form, said die likewise 90 having a downwardly-inclined, tapering bottom, with a centrally-disposed opening therein; projecting a kick-out die, having a rounded upper end, through said opening and into contact with the lower face of 95 the stock; then sinking a punch into the upper face of the stock, whereby the metal will be caused to flow to fill the lower portion of the die and around the kick-out die, and likewise caused to flow upwardly into the 100 space between the cylindrical wall of the die and the punch; and finally threading the blank thus produced.

7. The process of making hollow set-screws, which consists in placing a solid 105 piece of stock in a laterally-confining die; sinking a punch into one end thereof, whereby it will be elongated and a sink formed in one end; then subjecting the stock to a punch of smaller diameter and thereby causing further elongation of the blank and an inward movement of the metal thereof into contact with the punch; and finally exteriorly threading the blank thus produced.

8. The process of making hollow set-screws, which consists in placing a solid 115 piece of stock in a laterally-confining die; sinking a punch, polygonal in cross-section, into one end of the stock, whereby the stock will be forced into contact with the bottom 120 of the die and likewise elongated and caused to flow up about the punch; then sinking a punch of like but smaller cross-section into the opening or sink formed by the first punch, and simultaneously confining and condensing the upper edge of the blank; and finally exteriorly threading the blank thus produced.

9. The process of making hollow set-screws, from a solid piece of stock, which 130

consists in forming a sink in one end of the stock and simultaneously shaping the lower end thereof; then deepening and contracting the sink and simultaneously swaging the upper end of the blank being formed; and finally exteriorly threading the blank thus produced.

10. The process of making hollow set-screws, which consists in producing a sink in one end of a piece of stock and simultaneously forming a cup-shaped recess in the opposite end of the screw-blank and at the

same time elongating the stock; then swaging the blank to contract and elongate the sink and to finish the upper edge of the 15 blank; and finally exteriorly threading the blank thus produced.

In testimony whereof I have signed my name to this specification in the presence of two subscribing witnesses.
